(57) **CLAIM**

The ornamental design for a television receiver as shown and described.

DESCRIPTION

The patent or application file contains at least one drawing executed in color. Copies of this patent or patent application publication with color drawing(s) will be provided by the Office upon request and payment of the necessary fee.

1. Television receiver

1.1 : Perspective

1.2 : Rear perspective view

1.3 : Front

1.4 : Back

1.5 : Left

1.6 : Right

1.7 : Top

1.8 : Bottom

1.9 : Reference

1.10 : Reference

The broken lines depict portions of the article that form no part of the claimed design; the portion of the design shown in the color yellow is for the purpose of illustrating portions of the article that form no part of the claimed design; reproduction 1.9 is a reference view showing an alternative state of use; and reproduction 1.10 is a reference view showing another alternative state of use.

1 Claim, 10 Drawing Sheets

(4 of 10 Drawing Sheet(s) Filed in Color)
